DESIGN FOR A HANDLE BAR GRIP

John R. Morgan, Oak Park, Ill., assignor to Sears, Roebuck and Co., Chicago, Ill., a corporation of New York

Application April 24, 1936, Serial No. 62,270

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Handle Bar Grip, of which the following is a specification, reference being had to the accompanying drawing, forming a part thereof.

Fig. 1 is a side view,
Fig. 2 is a bottom view, and
Fig. 3 is a front end view of a handle bar grip embodying my new design.

I claim:

The ornamental design for a handle bar grip, as shown.

JOHN R. MORGAN.
